PAGE 2

FIG. 2.

FIG. 3.

*FIG. 4.FIG. 5.*FIG. 1 is a side elevational view of a truck, showing my new design;

FIG. 2 is an elevational view of the cab with the left wall removed;

FIG. 3 is a sectional view taken on lines 3—3 of FIG. 2;

FIG. 4 is an interior perspective view of the cab taken diagonally from the left rear;

FIG. 5 is an interior perspective view of the cab taken diagonally opposite FIG. 4; and

FIG. 6 is an interior plan view.

The characteristic features of my design reside in the interior of the truck cab as best shown in FIGS. 2 through 6.

I claim:

The ornamental design for a truck, as shown and described.
